PUMP

Filed Aug. 14, 1929

UNITED STATES PATENT OFFICE

FRED M. OEDER, OF FLINT, MICHIGAN

PUMP

Application filed August 14, 1929. Serial No. 385,724.

This invention relates to pumps for pumping water and liquids of various kinds.

The prime object of the invention is to provide a pump in which the conventional pump rods are eliminated, and in which all working parts are above the ground level, making it unnecessary to remove the entire pump for replacement or repair of the moving parts thereof.

10 Another object is to provide a pump of simple and substantial design in which the delivery spout can be in any desired location, with relation to the casing.

A further object is to provide a pump 15 which can be placed at any suitable water level and which will deliver a volume of water equal to the area of the casing between the end of the expansion plug and the end of the discharge pipe, making unnecessary the placing of a restricted cylinder in the casing where the water level is below the vacuum line and which accordingly limits the pump capacity.

A further object is to design a pump 25 with which a large volume can be secured from a small casing, which will operate efficiently with a limited supply; which is economical to manufacture and assembled, easy to install, and of rigid construction.

30 A further object still is to provide means for seating the expansion plug to produce a leak-proof joint after it has been lowered to position in the casing.

With the above and other objects in view, 35 the present invention consists in the combination and arrangement of parts hereinafter more fully described, illustrated in the accompanying drawing and particularly pointed out in the appended claim, it being understood that changes may be made in the form, size, proportion, and minor details 40 of construction without departing from the spirit or sacrificing any of the advantages of the invention.

In the drawing.

Fig. 1 is a view showing my improved pump.

Fig. 2 is an enlarged fragmentary sectional view thereof.

Fig. 3 is a plan view of the plug shown in Fig. 2.

Fig. 4 is an inverted plan of the opposite end of said plug.

Referring now particularly to the drawing, the numeral 5 indicates a stationary plunger which can be located in any convenient desired position above the ground level, an air cylinder 6 is reciprocatingly mounted on this plunger, the lower end being open and a rod 7 is pivotally connected to the upper end thereof. A vertically disposed leg or standard 8 is provided directly adjacent the cylinder and one end of a handle 9 is pivotally connected thereto at the point intermediate its length, this is however all of the conventional type and can be varied to suit a manual or power actuated installation.

A pipe line 11 is connected to the lower end of the air plunger 5 leading downwardly into a conventional casing 12, the lower end of said casing projecting into the water supply. An expansion plug 13 is secured in this casing at a point intermediate its length, said plug being of smaller diameter than the inside diameter of the casing, the lower end being shouldered and threaded as shown at 14, and a packing member 15 is mounted thereon, and is held in position by means of a tubular shoe 16, which is internally threaded to engage the threaded shouldered end of the plug. Resilient fingers 17 are riveted or otherwise suitably secured to the inner surface of the shoe, these fingers being bowed as shown, so that when the plug is in position, these fingers will frictionally engage the walls of the casing to hold and resist rotation of the shoe.

Spaced apart passages 18 and 19 are provided in the plug as shown, the upper end of the passage 18 being threaded and is adapted to receive the threaded end of the pipe line 11 which connects with the air cylinder, the opposite end being arcuate shaped so that the area of the passage will be uniform throughout. The opposite passage 19 is identical in shape, excepting that the lower end is round and threaded to receive one end of a discharge pipe 20, the upper end of

the passage being also arcuate shaped as clearly shown in Fig. 4 of the drawing.

The discharge pipe 20 projects downwardly into the casing, a check valve 21 being provided on the lower end thereof, a similar check valve 22 being provided in the end of the casing so that as the water is drawn into the casing, and particularly when the supply is limited, that it will be trapped therein, also in certain installations, and where conditions warrant, a check (not shown) can be used, this is however immaterial as it forms no part of the present invention. A discharge fitting 23 is provided on the upper end of the casing and through which the water is discharged, and a cap (not shown) covers the top of the casing and is provided with an opening therein to accommodate the air line.

In assembling the expansion plug 13 is lowered into the casing on the pipe line 11, and when the desired depth is reached, the pipe 11 is turned, screwing the plug against the packing, expanding it in the casing, and making a tight joint so that the plug will be rigidly held in position, to remove the plug from the casing, the operation is merely reversed.

In practice the operation of the pump is as follows. When the pump handle is in position as shown in Fig. 1 of the drawing, the cylinder is at the end of its downward stroke, this cylinder is now raised by forcing the handle upwardly, as shown in dotted lines in Fig. 1 of the drawing creating a suction so that the check valve 21 is closed and valve 22 is opened, this suction draws water into the casing below the expansion plug, the volume being governed by the area of the air cylinder. Reverse movement of the handle forces air through the pipe line 11 and into the casing below the plug, closes check valve 22 and opens the valve 21, forcing the liquid through the discharge pipe 20 into the casing above the plug, and thence out through pipe 23, continued actuation of the handle repeats the operation above described.

It is of course the prime object to provide a large volume from a small casing, and in order to accomplish this result one end of the passages 18 and 19 must be arcuate shaped and disposed in opposite directions, as it would be impossible (in a small casing), to secure sufficient stock for similar round openings on one end, and such as necessary to accommodate the air line and the discharge pipe.

In the accompanying drawing I have shown an air cylinder and a plunger with a handle connected thereto for manual operation, but it will be clearly obvious that any other suitable mechanism, either manual or power actuated may be employed.

From the foregoing description it will be obvious that I have perfected a very simple,

efficient, and economical pump for elevating liquids of various kinds.

What I claim is:—

A liquid pump comprising a casing, having a check valve on the lower end thereof, a plug mounted in said casing and having a shouldered threaded end, a packing mounted thereon, an interiorly threaded tubular shoe having threaded engagement with said threaded end for expanding said packing to form a leak-proof joint with the casing, resilient fingers secured to said shoe and frictionally engaging the casing passages in the plug, one end of each passage being threaded and adapted to receive an air line and a discharge pipe respectively, the opposite ends being arcuate shaped, said discharge pipe projecting downwardly into the casing and having a check valve in the lower end thereof, and means for alternately creating a suction and pressure in the casing below the plug, for sucking water into the lower end of the casing and exhausting water from the upper end thereof.

In testimony whereof I hereunto affix my signature.

FRED M. OEDER.
